MACHINE FOR APPLYING GLUE IN STRIPES
TO SHEET MATERIAL

Robert Minkow, New York, N. Y.

Application May 6, 1949, Serial No. 91,719

5 Claims. (Cl. 118—221)

1

This invention relates to gluing machines and is an improvement over the structure shown in my copending application Serial No. 2,270, filed January 14, 1948, for Gluing Machine, and now Patent No. 2,554,587.

An object of this invention is to provide a gluing machine wherein one or more ribbons of glue may be applied to an article at any selected point on the article.

Another object of this invention is to provide in a gluing machine one or more gluing rollers which are endwise adjustable so that the glue applied to the article may be applied at the desired point on the article, and the ribbon of glue may be of any selected width.

A further object of this invention is to provide a gluing machine wherein the adjusting means for the gluing roller or rollers may also serve the dual purpose of regulating the thickness of the glue coating.

A further object of this invention is to provide an improved work guide means on the table which may be adjusted to accommodate work of varying widths.

With the above and other objects in view, my invention consists in the arrangement, combination and details of construction disclosed in the drawings and specification, and then more particularly pointed out in the appended claims.

In the drawings,

Figure 1 is a plan view of a gluing machine constructed according to an embodiment of this invention,

Figure 2 is a plan view of the device, partly broken away and with the table removed,

Figure 3 is a fragmentary sectional view taken on the line 3—3 of Figure 1,

Figure 4 is a fragmentary sectional view taken on the line 4—4 of Figure 2,

Figure 5 is a fragmentary sectional view taken on the line 5—5 of either Figure 2 or 4,

Figure 6 is a fragmentary side elevation of the slotted roll adjusting bar,

Figure 7 is a fragmentary plan view, partly in section, of the slotted roll adjusting bar,

Figure 8 is a fragmentary sectional view taken on the line 8—8 of Figure 3,

Figure 9 is a fragmentary plan view of a modified form of this invention,

Figure 10 is a fragmentary sectional view taken on the line 10—10 of Figure 9.

Figure 11 is a sectional view of another modification of glue roller shaft and lock for the glue roller.

Referring to the drawings, the numeral 15 des-

2

ignates generally a base structure formed with upstanding side walls 16, end walls 17 and 18, and a bottom wall 19. The upstanding walls 16, 17 and 18 form a well within which glue is adapted to be positioned.

A gluing roller shaft 20 extends across the gluing well 21 and is journaled in a pair of bearings 22 which are positioned in vertically disposed slots 23 formed in the side members 16. The ends of the shaft 20 are reduced, as indicated at 24, with the reduced ends 24 rotatably mounted in the bearings 22. The bearings 22 are formed with a pair of vertical flanges 25 which are adapted to engage the inner sides of the side walls 16, as shown in Figure 2.

The shaft 20 is formed with a longitudinally extending keyway 26 within which a key 27 is adapted to be positioned. A pair of gluing rollers 28 are mounted on the shaft 20 and each gluing roller is formed with a keyway 29 within which the key 27 is adapted to slidably engage.

The rollers 28 are adapted to be adjusted relative to each other along the length of the shaft 20, as will be hereinafter described, so that a pair of ribbon-like gluing strips may be applied to an article which is moving over the gluing rollers 28.

The shaft 20 is provided at one end thereof with a gear 30 which is interposed in a reduction gear train 31 of conventional construction and which is operated by means of a motor M disposed at the rear of the base frame 15. The rollers 28 are adapted to be adjusted relative to each other by means of a pair of plates 32 which are disposed on the upper side of a polygonal bar 33 extending across the sides of the frame 15. Each plate 32 is formed with a U-shaped slot 34 confronting a roller 28 so that a portion of the roller 28 may engage in the slot 34. These plates 32 not only provide for holding the rollers 28 in adjusted position relative to each other, but also provide a means for regulating the amount of glue which is retained on the periphery of each roller for application to the article passing thereover.

The bar 33 is formed with an inverted T-shaped slot 35 extending lengthwise thereof, and a right angularly disposed and upwardly opening slot 36 is formed in the bar 33 so that the head 37 of a bolt 38 may be inserted or removed from the T-shaped slot 35. A wing nut 39 is threaded on the bolt 38 and is adapted to tightly hold the plate 32 in lengthwise adjusted position with respect to the bar 33. The opposite ends of the bar 33 engage in an upwardly opening notch 40 which is formed in each side member 16, with the notch 40 substantially longer than the width of the bar

55

33 so that the latter may be adjusted lengthwise of the notch 40 and the inner edge 41 of the slot 34 may be adjusted toward or from the roller 28.

A pair of elongated bar adjusting rods 42 are secured at their forward ends to the projecting ends of the bar 33 and engage through a notch 43 which is formed in an outwardly offset lug or enlargement 44 carried by each side member 16. A locking pin 45 is extended through the enlargement 44 engaging over the rod 42 and as shown in Figure 4, the rod 42 is formed with an elongated cut-out 46 within which the locking pin 45 is adapted to loosely engage. The rod 42 extends rearwardly, engaging through a notch 47 formed in the rear lug 48 projecting from the base 15, and a pair of rod adjusting nuts 49 and 50 are threaded on the rear portion of the rod 42.

A spring 51 engages about the rod 42, bearing at its forward end against a collar 52 which is fixed on the rod 42 and bearing at its rear end against a washer 53 positioned about the rod 42 and interposed between the rear end of spring 51 and the forward side of lug 48.

The bar 33 adjacent each end thereof has secured thereto a pair of angle members 54 which are adapted to bear against the inner faces of the side members 16 so that the bar 33 will be held against lateral shifting, but will be permitted to have longitudinal shifting or adjustment within the notches 40.

The base 15 has mounted above the well 21 an elongated work feeding table 55 which is secured to a pair of elongated bars or arms 56 pivoted, as at 57, to the forward portion of the base 15. The bars 56 include upstanding lugs 58 between which a pair of pressure rollers 59 and 60 are rotatably mounted. The pressure rollers 59 and 60 are disposed above the gluing rollers 28 on opposite sides of the longitudinal axes of the rollers 28, as shown in Figure 3. The articles which are being fed to the gluing rollers 28 are guided over the table 55 by means of a pair of elongated angle-shaped guide members 61 which are disposed on the upper side of the table 55.

Each angle member 61 has secured thereto a laterally projecting bar 62 formed with an elongated slot 63 through which a bolt 64 engages. The bolt 64 extends through the table 55 and a wing nut 65 is threaded onto the bolt 64. After the work has passed over the gluing rollers 28, the work is stripped from the gluing rollers by means of pairs of stripping fingers 66 which are pivotally mounted on an elongated bar 67 disposed between the side members 16 adjacent the forward portions of the latter.

Referring now to Figures 9 and 10, there is disclosed a slightly modified form of this invention. The gluing roller 28a is slidably mounted on the shaft 20a formed with a keyway 26a, and a screw 68 is threaded through the hub 69 of roller 28a and projects into the keyway 26a. Each roller 28a is adjusted lengthwise of the shaft 20a by means of a plate 32a formed with a U-shaped slot 34a, and the plate 32a slidably engages on the upper side of a supporting bar 33a. The bar 33a is formed in the rear side thereof with a T-shaped slot 35a and the plate 32a is provided with a right angular flange 70 engaging the rear slotted side of bar 33a.

The head 71 of a bolt 72 engages in the slot 35a and a nut 73 is threaded on the bolt 72 and is adapted to secure the plate 32a in adjusted position along the length of the bar 33a.

In the use and operation of this machine, the article guide members 61 are adjusted relative to

each other so that the articles may freely slide lengthwise thereof over the table 55. The gluing rollers 28 are adjusted relative to each other so that the rollers will contact with the article at predetermined points on the lower surface of the article. As the article passes over the gluing rollers and beneath the pressure or feeding rollers 59 and 60, the article will have glue applied in a pair of strips, and the article after passing over the gluing rollers 28 will be stripped therefrom by the stripping fingers 66.

In Figure 11 there is disclosed another modification of this invention wherein the shaft 20b is formed with a flat surface 75 extending lengthwise thereof, and a brass plug 76 loosely engaging in a threaded hole 78 formed in hub 69b of glue roller 28b is held tight against shaft 20b by means of a set screw 79.

It will, of course, be understood that there may be as many of these gluing rollers as may be desired and where only a single narrow strip is to be glued, only one of these rollers will be used and this roller adjusted to contact with the article at a predetermined point on the article.

I do not mean to confine myself to the exact details of construction herein disclosed, but claim all variations falling within the purview of the appended claims.

What I claim is:

1. A gluing machine comprising a base formed with a glue well, a table engaging over said well, a shaft rotatably carried by said base and extending across said well, said shaft having a longitudinal key engaging surface, a gluing roller slidably carried by said shaft, having a key means engaging said surface for simultaneous rotation with sliding movement of said roller on the shaft, a pair of feeding rollers disposed over said gluing roller, and means offset from said gluing roller and engageable therewith for adjusting said gluing roller lengthwise of said shaft, said adjusting means including means for regulating the depth of glue retained on said gluing roller for application to an article passing over the latter.

2. A gluing machine comprising a base formed with a glue well, a table engaging over said well, a shaft rotatably carried by said base and extending across said well, said shaft having a longitudinal key engaging surface, a gluing roller slidably carried by said shaft and having a key means engageable with said surface for simultaneous rotation with sliding movement of said roller on said shaft, and means offset from said gluing roller for adjusting said gluing roller lengthwise of said shaft, said adjusting means including a yoke-shaped member engaging the opposite ends of said gluing roller, and horizontally movable supporting means for said member, said supporting means comprising an elongated bar formed with an inverted T-shaped slot lengthwise thereof, a headed bolt having the head thereof slidable in said slot, and a nut threaded on said bolt for clamping said yoke-shaped member in adjusted position lengthwise of said bar.

3. A gluing machine comprising a base formed with a glue well, a table engaging over said well, a shaft rotatably carried by said base and extending across said well, said shaft having a longitudinal key engaging surface, a gluing roller slidably carried by said shaft and having a key means engageable with said surface for simultaneous rotation with sliding movement of said roller on said shaft, a pair of feeding rollers disposed over said gluing roller, and means offset

from said gluing roller for adjusting said gluing roller lengthwise of said shaft, said adjusting means including a yoke-shaped member engaging the opposite ends of said gluing roller, a supporting bar for said member loosely carried by said base and disposed in parallel relation with respect to said shaft, and means for adjusting said bar toward or from said shaft.

4. A gluing machine comprising a base formed with a glue well, a table engaging over said well, a shaft rotatably carried by said base and extending across said well, a full longitudinal keyway in said shaft, a gluing roller slidably carried by said shaft and key means engaging in said keyway carried by said roller for simultaneous rotation thereof with said shaft, a pair of feeding rollers disposed over and beyond each end of said gluing roller, and means offset from said gluing roller for adjusting said gluing roller lengthwise of said shaft, said adjusting means including a plate formed with a notch within which said gluing roller is adapted to loosely engage, a supporting bar for said plate extending over said base in parallel relation with respect to said shaft, means for clamping said plate in adjusted position along the length of said bar and means for adjusting said bar toward or from said shaft.

5. A gluing machine comprising a base formed with a glue well, a table engaging over said well, a shaft rotatably carried by said base and ex-

tending across said well, a full longitudinal keyway in said shaft, a gluing roller slidably carried by said shaft, a key carried by said roller engaging in said keyway for simultaneous rotation of said roller with said shaft, a pair of feeding rollers disposed over and extending beyond the ends of said gluing roller, and means adjusting said gluing roller lengthwise of said shaft throughout the length of said feeding rollers, said adjusting means including a plate formed with a notch within which said gluing roller is adapted to loosely engage, a supporting bar for said plate extending over said base in parallel relation with respect to said shaft, means for adjusting said bar toward or from said gluing roller, and means for clamping said plate in adjusted position along the length of said bar.
